CLAIM

The ornamental design for attachment for sliding a rotary string trimmer, as shown and described.

DESCRIPTION

FIG. 1 is an attachment for sliding a rotary string weed trimmer showing my new design with the opposite side being a mirror image except for the absence of the notch at the end;

FIG. 2 is a top plan view thereof;

FIG. 3 is a front end view thereof;

FIG. 4 is a rear end view thereof; and,

FIG. 5 is a sectional view taken upon the line 5—5 of FIG. 2.

The undisclosed bottom plan view is planar and unornamented.

FIG. 1

FIG. 2

FIG. 3

FIG. 5

FIG. 4
